UNITED STATES PATENT OFFICE

157,961

ORPHREY OR SIMILAR ARTICLE

Joseph L. Katz, New York, N. Y.

Application October 27, 1949, Serial No. 5,738

Term of patent 7 years

(Cl. D3—32)

To all whom it may concern:

Be it known that I, Joseph L. Katz, a citizen of the United States of America, residing in New York city, county and State of New York, have invented a new, original, and ornamental Design for an Orphrey or Similar Article, of which the following is a specification, reference being had to the accompanying drawing, forming part thereof.

In the drawing:

The figure is a plan view of an orphrey embodying my new design.

I claim:

The ornamental design for an orphrey or similar article, substantially as shown.

JOSEPH L. KATZ.
